UNITED STATES PATENT OFFICE.

JOHN E. KENNEDY, OF GLENS FALLS, NEW YORK.

AUDIBLE SPEEDOMETER.

1,420,633.

Specification of Letters Patent. Patented June 27, 1922.

Application filed December 17, 1919. Serial No. 345,879.

To all whom it may concern:

Be it known that I, JOHN E. KENNEDY, a British subject, and resident of Glens Falls, in the county of Warren and State of New 5 York, have invented certain new and useful Improvements in Audible Speedometers, of which the following is a specification.

This invention is intended to provide an 10 audible speedometer which will act to warn the driver by an audible signal when the car reaches or maintains a speed in excess of a predetermined rate of speed. It thus frees the eyes of the driver from continual observation of the visible mileage indicating speedometer and automatically warns him when he unwittingly passes any predetermined rate of speed, thereby increasing the safety and pleasure of driving. It also informs the passenger when the car is being 15 driven at a speed in excess of a given rate.

The invention consists primarily in combining with a speed governed member or shaft, an audible signaling device so that when the car is being driven in excess of a 20 given rate of speed the signal automatically sounds and continues to sound a warning.

By progressively increasing the number 25 of signaling devices in suitable relationship to and coordination with the speed controlled member, giving each a distinctive sound, a complete series may be employed covering the whole range of motor car speeds, at such intervals as may be desired. Another feature of the invention consists 30 in providing means by which any individual signal may, as desired, be rendered non-responsive to speed acceleration, thereby rendering the signaling system a selective one.

In the accompanying drawings I have 35 illustrated two of the various forms that may be utilized to embody the principles of this invention in which—

Figure 1 is a side elevation showing the 40 device as applied to the dash of a motor car.

Figure 2 is a front elevation showing the 45 arrangement of the parts on the dash, the electric circuits being indicated diagrammatically in dotted lines.

Figure 3 is an enlarged longitudinal central section illustrating the working parts 50 of the device.

Figure 4 is a cross section through the 55 controlling member with the electric circuit and signal indicated diagrammatically.

Figure 5 is a central longitudinal section 55 of the terminal containing member showing the interior of the two halves.

Figures 6, 7 and 8 are detail views showing the application of the invention directly to a dial pointer type of speedometer. 60

For convenience and certainty I prefer to use electrically operated signaling devices such for example as electric buzzers of the well-known construction which are capable of being set to give different or distinctive 65 sounds so that one signal may be audibly distinguished from another. In both the electrically operated forms of the device herein described the electric circuit which includes the buzzer mechanism leads to terminals through which, by means of an automatic controlling device, the electric current is controlled to cause the alarm to sound when the circuit closing device, whose movement is governed by the speed of the car, is 70 moved beyond a predetermined position.

In the practice of the invention according to the form illustrated in Figure 1, I mount upon the speedometer shaft *a* a centrifugal governor *b* one collar *b'* of which is fixed 80 to the shaft *a* while the free or sliding collar *b* is in the form of a circuit closing plug *b*² of insulating material which carries a peripheral ring *b*³ of copper or suitable conducting material forming a bridge for establishing 85 electrical connection between the various terminals that are carried by the surrounding tubular terminal supporting member *d*.

The terminal supporting member *d* is 90 preferably made of tubular form and of non-conducting material and carries on one side a longitudinal terminal or contact member *e* which is common to all the electric circuits. On the other side are inserted any desired number of terminal members corresponding to the number of circuits and signals desired to be used. In this case two such terminals are shown at *f* and *g* through which leads respectively wires *f'* and *g'* for establishing circuits through the manually 100 controlled switches *f*² and *g*² and the electric buzzers *f*³ and *g*³.

It will be noticed particularly by reference to Figure 5 that the independent terminals *f* and *g* controlling the buzzers *f*³ and *g*³ respectively are of different length. When the speed of the flexible speedometer shaft *a* reaches a predetermined point, say for ex- 105

ample 15 miles an hour, the ball governors *b* will throw out a certain distance against the pressure of the compressed spring *c* thus causing the circuit closing plug *b*² to move 5 axially along the shaft toward the dash *A*. At this predetermined speed the electric bridge or connecting ring *b*³ closes the circuit by establishing electric connection between terminal *e* and the initial end of terminal *f* so as to permit the current to flow 10 through the buzzer *f*³ thereby sounding the alarm.

If the speed of the car be increased to a speed, let us say 25 miles per hour, the further longitudinal traverse of the circuit closing plug acts to establish electric connection 15 between the terminal *e* and the terminal *g* whose initial end is nearer the dash than the initial end of terminal *f*. At this stage, 20 therefore, the circuit being complete through terminals *g* and *e* the current flows through buzzer *g*³. The buzzers preferably should be adjusted to emit sounds of different pitch so that the driver, without looking at the speedometer, will know by hearing the second 25 buzzer that the next higher speed has been reached.

The selective principle can be introduced 30 into effective use in this apparatus by providing any suitable form of switch such as a push button switch at *f*² and *g*² in the respective circuits so that by opening this switch normal operation of any individual signaling device may be prevented at will. 35 The course of the electric circuit through the terminals, the manually controlled switches and the separate alarm devices is diagrammatically illustrated in Figure 4.

Instead of applying a mechanical governor to the speedometer shaft or other speed actuated member, the terminals may be assembled directly upon the speedometer device itself particularly in that type of speedometer which uses a pointer fixed to a rotatable arbor in connection with a circular dial face, and I have shown in Figures 6, 7 and 8 how this invention may be applied to a speedometer of such a type.

On the arbor *o*' of the speedometer *o* is 50 secured an insulated disk *r* in which is inserted a radial terminal member *r*' in electric contact with the arbor *o*' at its inner end and with its outer end flush with the periphery of the disk and extending through 55 the thickness of the disk.

Inside the speedometer casing are mounted two separate terminals *s* and *t* so adjusted that when the arbor *o*' is moved to the position indicative of any given speed, say 15 60 miles an hour, the first terminal *s* will be in electric contact with the circuit closer *r*' and thus energize the circuit *s*' leading to the appropriate signal or alarm and continuing to sound it so long as the speed exceeds 15 65 miles per hour. A further increase in speed

accompanied by the further rotation of the disk *r* brings the circuit closer *r*' with the next terminal *t* through which the current flows along wire *t*' to the corresponding buzzer or signal as already explained in respect to the form of construction shown in Figure 1.

While the open terminals *f* and *g* are shown beginning at different points along the line of traverse of the circuit closer so as to be closed at different points of said traverse it will be observed that the lower speed terminal overlaps or extends beyond the initial point of the higher speed terminal so that the signal indicative of the lower speed may continue to sound even after the higher speed has been reached. As each signal has its distinctive sound, their simultaneous sounding gives unmistakable indication of speed at or above the higher speed indicated so that there can be no such confusion as might result from having each signal cease to sound when the critical speed at which the signal acts is exceeded. Moreover the inaction of any lower speed indicator when a higher speed indicator is acting would give notice of some defect, unless such lower speed indicator were cut out by the manual switch in its circuit.

What I claim is:

1. A speed indicating apparatus for a motor car embracing in combination a plurality of audible electrically operated signaling devices, an electric circuit leading to each signal and including an open terminal 100 separate from the terminal of the other circuit, a circuit closer whose movement is determined by the speed of the car arranged to close the different circuits in succession and a cut out switch arranged in each electric circuit to render the individual signals incapable of normal operation, substantially as described.

2. A speed indicating apparatus for a motor car embracing in combination a rotary 110 shaft whose speed of rotation varies according to the speed of the car, a tubular terminal supporting member provided with terminals of different length, a circuit closing member movable by means of said shaft into 115 contact successively with said terminals, a buzzer in circuit with each separate terminal and a manually controlled switch for opening or closing said circuit at will, substantially as described.

3. A speed indicating apparatus for a car, embracing in combination a plurality of audible signals audibly distinguishable from one another, a plurality of open electric circuits one for each audible signal each operating when closed to sound its own signal, a circuit closer controlled according to the speed of the car and acting to close the respective signal circuits at different speeds of the car and to keep each circuit closed 130

while the car maintains or exceeds the critical speed at which said circuit is closed, substantially as described.

4. A speed indicating apparatus for a car, embracing in combination a plurality of audible signals audibly distinguishable from one another, a plurality of open electric circuits one for each audible signal each operating when closed to sound its own signal, a 10 circuit closer controlled according to the speed of the car and acting to close the respective signal circuits at different speeds of the car and to keep each circuit closed while the car maintains or exceeds the critical 15 speed at which said circuit is closed, a cut out switch arranged in each circuit to render the same inoperative at will, substantially as described.
5. A speed indicating apparatus for cars, 20 embracing in combination, a plurality of distinctive audible signals, included in separate electric circuits that are open when the car is not running above a predetermined speed, a movable circuit closer whose 25 position is progressively shifted according to the increasing speed of the car to close in succession the open terminals of each circuit, said terminals being extended to con-

tinue in contact with the circuit closer so 30 long as the circuit closer is maintained at or beyond the point of its initial contact with said closer, whereby two or more of the signals will be sounding simultaneously while the car speed is maintained at a point cor- 35 responding to one or more of the signals indicative of the higher speeds, substantially as described.

6. A speed indicating apparatus for a car, embracing in combination, a plurality of 40 open electric circuits, a plurality of audible signals audibly distinguishable from one another arranged in the respective circuits to be operated when their respective circuits are closed, a circuit closer movable in relation to the open terminals of said circuits to 45 close them in predetermined succession when the car reaches predetermined rates of speed, and means for shifting said circuit closer according to the change in speed of the car whereby the car operator is kept audibly informed of the speed rate of the car without 50 visual inspection of a speed indicator, substantially as described.

In witness whereof, I have subscribed the above specification.

JOHN E. KENNEDY.
